DESIGN FOR A FOUNTAIN PEN OR SIMILAR ARTICLE

John Hill, Hillside, N. J., assignor to Celluloid
Corporation, a corporation of New Jersey

Application May 1, 1936, Serial No. 62,399

Term of patent 7 years

To all whom it may concern:

Be it known that I, John Hill, a subject of the King of England, residing at Hillside, county of Union, State of New Jersey, have invented a new, original, and ornamental Design for a Fountain Pen or Similar Article, of which the following is a specification, reference being had to the accompanying drawing, forming part thereof.

In the accompanying drawing:

The figure is a plan view of a fountain pen showing my new design.

The ornamentation of the fountain pen shown in the drawing comprises a dark background, having short, narrow vertical strips of a contrasting color presenting pearl luster effects.

I claim:

The ornamental design for a fountain pen, substantially as shown and described.

In testimony whereof, I have hereunto subscribed my name.

JOHN HILL.
